UNITED STATES PATENT OFFICE.

JAMES T. ALLEN, OF KILBOURNE, LOUISIANA.

BOTTLE CLOSURE.

Application filed October 29, 1923. Serial No. 669,775.

To all whom it may concern:

Be it known that I, JAMES T. ALLEN, a citizen of the United States, residing at Kilbourne, in the parish of West Carroll 5 and State of Louisiana, have invented certain new and useful Improvements in Bottle Closures, of which the following is a specification.

This invention relates to certain new and 10 useful improvements in bottle closures, and has particular reference to closures of that type embodying a cap having means for automatically permanently attaching the same to the bottle when operatively disposed over the neck of the latter.

The primary object of the invention is to provide a bottle closure of the above kind, which embodies the desired qualities of simplicity, and durability of construction, as well as efficiency in operation.

A further object of the invention is to provide a bottle closure including a cap member adapted to be mutilated before access is had to the contents of the bottle.

Still another object of the invention is to provide a cap member adapted to be so mutilated as to leave a portion thereof upon the bottle neck for acting as means to indicate that the original contents of the 20 bottle have been removed and to thereby discourage refilling of bottles.

Other objects will appear as the nature of the invention is better understood, and the same consists in the novel form, combination, and arrangement of parts herein-after more fully described, shown in the accompanying drawings and claimed.

In the drawing, wherein like reference characters indicate corresponding parts 40 throughout the several views:

Figure 1 is an elevational view, showing a bottle closure operatively associated with a bottle neck and constructed in accordance with the present invention.

Figure 2 is a central vertical sectional view of a device shown in Figure 1.

Figure 3 is a horizontal transverse sectional view, taken upon the line 3-3 of Figure 1.

Figure 4 is a central vertical sectional view of the cap removed from the bottle neck, and

Figure 5 is an elevational view of a key adapted to be employed for mutilating the cap when access is desired to be had to the contents of the bottle.

Referring more in detail to the drawing, the present invention embodies a sheet metal cap 5 having a relatively long skirt portion that is weakened along a pair of spaced parallel circumferentially extending lines 6 to define an intermediate skirt portion that is removable for mutilating the cap and permitting detachment of the portion of the cap thereabove for permitting access to the interior or contents of the bottle as will presently become apparent. This removable portion of the skirt has an outstanding tab 7 adapted to be engaged in a slot 8 of a suitable key 9 whereby, when said key is rotated, the removable portion of the skirt is wound thereon and forcibly removed.

Rigid with the lower end of the skirt of the cap 5 are a pair of superposed arcuate jaw plates 10 that extend upwardly within the cap and terminate in inturned upper ends as at 11, at a point below the top of the cabinet shown in Figures 2 and 4. The jaws 10 may be formed as integral extensions from the skirt of the cap and are of a resilient nature so that the upper ends thereof are normally sprung in position to automatically engage behind shoulders 11 provided externally upon opposite sides of the neck 12 of a suitable glass receptacle or bottle when the cap is placed over said neck as shown in Figure 2, whereby the cap is permanently and automatically locked upon the neck of the bottle.

In order that the cap may be of durable construction, the lower end of the skirt portion thereof may be formed with a bead 13 at the point of connection between said skirt and the jaws 10.

In the use of the present invention, the bottle neck is closed in the usual manner by a suitable cork plug 14, after which the cap 5 is placed over the neck so that the jaws 10 engage behind the shoulders 11 and permanently attach the cap in place. When it is desired to gain access to the contents of the bottle, the tab 7 is engaged in the slot 8 of the key 9 and the latter is then rotated so as to mutilate the cap 5 by forcible removal of the skirt portion between the weakened lines 6. When this is done, the crown portion of the cap is removed and the lower portion of the skirt of the cap 5 is left upon the neck of the bottle to act as an indicating means that denote that the original contents of the bottle have been re-

- moved. Upon removal of the upper portion or crown of the cap, the plug or cork 14 may be readily removed for allowing emptying of the contents of the bottle.
- 5 From the foregoing description it is believed that the construction and operation, as well as the advantages of the invention will be readily understood and appreciated by those skilled in the art.
- 10 Minor changes may be made without departing from the spirit and scope of the invention as claimed.
- What I claim as new is:
1. A bottle closure comprising a metal cap 15 adapted to fit over the neck of the bottle, said cap being adapted to be of a diameter greater than the neck which it surrounds to space the skirt portion thereof from said neck, said skirt portion of the cap being 20 divided into upper and lower sections by a readily removable band, said band being defined by vertically spaced circumferential incisions susceptible to easy disruption, a laterally disposed lug connected with one 25 end of said band and to facilitate removal thereof, and a pair of bottle engaging jaws disposed within said skirt and connected at their lower ends to the corresponding end of the latter, the upper free end of the said jaws being directed inwardly toward each other to engage beneath a shoulder with which the said aforesaid bottle neck is equipped.
  2. A bottle closure comprising a metallic cap to fit over the upper end of a bottle neck, 35 the lower end of the skirt of said cap being formed into a circumferential bead, the intermediate portion of said skirt being provided with a readily removable band dividing said skirt into upper and lower sections, 40 one end of said band being equipped with a laterally disposed lug, a pair of resilient jaws disposed within the skirt of said cap and having their lower ends curled around the adjacent portions of said bead to connect the jaws with the skirt, the upper free ends of said jaws being directed inwardly toward each other to engage with a shoulder with which the bottle neck is equipped for maintaining the closure in effective position. 45

In testimony whereof I affix my signature.
JAMES T. ALLEN.
